(57) **CLAIM**

The ornamental design for a combined helmet eye shield and visor, as shown and described.

DESCRIPTION

FIG. 1 is a perspective illustration, from the front and left side, of a first embodiment of the combined helmet eye shield and visor according to our design, the visor being shown in the lowered position;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective illustration, from the front and left side, of the first embodiment of the combined helmet eye shield and visor according to our design, the visor being shown in the raised position;

FIG. 8 is a front elevational view thereof;

FIG. 9 is a right side elevational view thereof;

FIG. 10 is a left side elevational view thereof;

FIG. 11 is a top plan view thereof;

FIG. 12 is a bottom plan view thereof;

FIG. 13 is a perspective illustration, from the front and left side, of a second embodiment of the combined helmet eye shield and visor according to our design, the visor being shown in the lowered position;

FIG. 14 is a front elevational view thereof;

FIG. 15 is a right side elevational view thereof;

FIG. 16 is a left side elevational view thereof;

FIG. 17 is a top plan view thereof;

FIG. 18 is a bottom plan view thereof;

FIG. 19 is a perspective illustration, from the front and left side, of the second embodiment of the combined helmet eye shield and visor according to our design, the visor being shown in the raised position;

FIG. 20 is a front elevational view thereof;

FIG. 21 is a right side elevational view thereof;

FIG. 22 is a left side elevational view thereof;

FIG. 23 is a top plan view thereof; and,

FIG. 24 is a bottom plan view thereof.

In each of FIGS. 1-24, the broken lines showing structure are for illustrative purposes only and form no part of the claimed design.
